CLAIM

The ornamental design for a vehicle seat cushion, as shown and described.

DESCRIPTION

FIG. 1 is a perspective view of a vehicle seat cushion showing my new design;

FIG. 2 is a front elevational view thereof;

FIG. 3 is a side elevational view thereof, the side opposite and the rear being identical to that shown;

FIG. 4 is a top plan view thereof, the bottom plan view being a mirror image of the top view shown in FIG. 4; and,

FIG. 5 is a cross-sectional view thereof taken along line 5—5 in FIG. 1.

FIG. 1

FIG. 2

FIG. 3

FIG. 4

FIG. 5
